UNITED STATES PATENT OFFICE.

BEULAH S. COHEN, OF DENVER, COLORADO.

DESIGN FOR A CHRISTMAS BAG.

Application filed February 12, 1926. Serial No. 16,503. Term of patent 7 years.

To all whom it may concern:

Be it known that I, BEULAH S. COHEN, a citizen of the United States, residing at the city and county of Denver, and State of Colorado, have invented a new, original, and ornamental Design for Christmas Bags, of which the following is a specification, reference being had to the accompanying drawing, forming part thereof, and in which:—

bag; and Figure 2 is a rear view of the Christmas bag.

I claim:

The ornamental design for a Christmas bag, as shown.

In testimony whereof I affix my signature.

BEULAH S. COHEN.
